UNITED STATES PATENT OFFICE

2,009,839

THERMIONIC CATHODE

Clifton G. Found, Schenectady, N. Y., assignor to
 General Electric Company, a corporation of
 New York

Application April 5, 1930, Serial No. 441,986

8 Claims. (Cl. 176—126)

The present invention relates to thermionic cathodes suitable for use in electrical discharge devices, for example such as glow lamps.

It is one of the objects of my invention to provide thermionic cathodes which are operable with a minimum of heating energy and minimum electrical disintegration. One of the features of my improved cathode is its configuration as a funnel-shaped hollow body.

10 The novel features of my invention will be further pointed out in the accompanying claims. My invention is illustrated in the accompanying drawing; Fig. 1 is a plan view of a gaseous glow lamp embodying my invention; Fig. 2 illustrates 15 a modified mounting; Fig. 3 is an enlarged detail view partly in section of my improved cathode; and Fig. 4 illustrates a modification which is unprovided with a cover.

Referring to the drawing, and in particular to 20 Fig. 3, a cathode embodying my invention comprises a hollow, elongated shell 1, consisting of suitable sheet material, such as nickel, iron, or other base metal which is coated on its inner surface with a material 2 of high electron emissivity, 25 for example, an alkaline earth material, such as barium oxide. The outside surface of the cathode preferably is shiny. The cathode is maintained at an operating temperature by a suitable heater various forms of which are known. The 30 particular heater illustrated in the drawing consists of a wire 3 of tungsten, tantalum, or other refractory metal wound on a support 4 of suitable refractory insulating material, such as beryllia, thoria, alumina, or magnesia. A conductor 5 35 consisting of molybdenum or tungsten passes through the insulating support 4 and is electrically connected to one end of the resistance heater at 6. The opposite end of the heater is suitably connected to the shell 1 as indicated at 7.

40 The main portion of the shell 1 which is coniform or funnel-shaped is provided with end closures 8, 9 joined by welding or otherwise to the main portion. The closure for the large end of the shell has an opening 10 of lesser diameter 45 than the diameter of said larger end through which an electrical discharge may pass. As shown in Fig. 4 the end closure, or cover 9, in some cases may be omitted. However, its presence is desirable as it reduces loss of heat and active coating material from the cathode. A surrounding shell 11 spaced about the cathode, as shown in Fig. 4, may be employed to conserve 50 heat in the cathode.

55 My present invention is an improvement over prior inventions made by Albert W. Hull, which

are described and claimed in applications Serial No. 156,713, filed October 9, 1925, and Serial No. 226,275, filed November 22, 1926 (see corresponding British Patents 282,766 and 298,906).

The cathode is mounted in a suitable vitreous envelope 12, as shown in Fig. 1, being supported by wires 13 and 14, the wire 13 being welded, or otherwise joined, to the conductor 5, and the wire 14 being joined to the shell 1. These wires 13 and 14 are sealed into a glass stem 15 and are 10 joined to the external conductors 16, 17. Although it is desirable that the cathode mounting should be arranged as shown in Fig. 1 to bring its smaller diameter nearest the discharge and the discharge opening therein remote from the anode 15 so as to cause the discharge to sweep over the surface of the cathode, such an arrangement need not be used invariably. An alternative arrangement is shown in Fig. 2.

The lamp shown in Fig. 1 also is provided with 20 anodes 18 and 19, having conductors 20, 21 which are sealed into glass stems 22, 23 of branches 24, 25 of the main envelope extending at right angles thereto as illustrated.

The envelope is exhausted by known approved 25 methods which are employed in the manufacture of a lamp, such as described, and then is charged with a suitable luminescent gas or vapor, such as neon, helium, mercury vapor or a mixture of gases, at a desired pressure. A neon filling having a pressure of about two mm. of mercury may be employed.

A gaseous glow device containing a thermionic electrode of the form and arrangement herein shown and described the diameter of which increases along its major axis is operable at increased net lighting efficiency and with a longer life.

In an electrical discharge device of the character shown positive ions are produced by ionization 40 of gas. Some of the positive ions strike the walls of the envelope and there combine with electrons and instead of becoming normal atoms are converted to atoms containing potential energy, which are known as metastable atoms. In colliding with a negative electrode, the metastable atoms give up their energy causing the emission of secondary electrons, sputtering of the electrode material, and clean-up of gas. The metastable atoms, however, become inactive or 45 are destroyed if such electrode or the space adjacent to it is irradiated by the electrical discharge in the gas. As a consequence, if the electrode area, which is exposed to bombardment by metastable atoms also is exposed to radiations 50

- of the gaseous discharge, metastable atoms can not exist long enough to produce emission of secondary electrons and other deleterious effects at the electrodes.
5. The conical shape and the arrangement of the cathode with respect to the anodes as shown in Fig. 1 exposes the exterior surface of the cathode to radiation from the discharge in the gas, thus protecting the cathode from undesired bombardment by metastable atoms.
10. The form and arrangement of the cathode also exposes it to a maximum extent to the heating effect of the discharge, thus reducing the heat input required to be furnished by the heater 6.
15. A large portion of the heat imparted by the discharge to a cathode is given up nearest the mouth of the cathode from which the discharge emanates. This part of the cathode will not become overheated as its area and hence also its heat dissipating capacity is larger than the small end of the cathode adjacent the cap 8. The closure 9, with its relatively small opening 10, conserves both loss of heat and of active material from the cathode and thereby increases both its heating 20 efficiency and its life. The closeness of the small end 8 of the cathode to the internal heater and its relatively small mass permits it to be heated up rapidly when the lamp is put into operation and thus reduces the initial starting period which 25 is required to bring a portion of the cathode to an electron-emitting temperature in order to start the gaseous discharge.
- Broad claims to the hollow or cavity cathode construction disclosed herein appear in the co-pending application of A. W. Hull, Serial No. 156,713, filed December 23, 1926. That application also contains claims relating to the combination of a cathode and heat shielding means. The 30 claims in the present application, therefore, are limited to improvements over the invention described and claimed in the application referred to above.
- What I claim as new and desire to secure by Letters Patent of the United States is:
45. 1. A thermionic cathode for electrical discharge devices comprising an elongated funnel-shaped shell an electronically active coating on the interior of said shell, said shell being open to the exterior at the region of greater diameter and a resistance heater mounted in said shell.
50. 2. In a gaseous glow lamp, the combination of a thermionic cathode comprising an elongated hollow body having one end thereof open and the opposite end closed, the open end being of materially greater cross-section than the closed end, and a coating of material of high electron emissivity on the interior of said body, a separate heater for said cathode, an anode, an enclosing envelope, and a luminosity producing gas therein.
55. 3. In an electron discharge device the combination of a thermionic cathode comprising a funnel-shaped hollow body closed at its small end and open to the exterior at its large end, a coating of material of high electron emissivity on an interior surface of said body, an electrical heater
5. mounted within said body, an anode remote from said cathode, an enclosure for said electrodes, and a gaseous filling at a pressure at which the heating of said cathode by an ionization discharge in said gas is appreciable.
4. A thermionic cathode comprising a base metal shell the diameter of which increases along its axis, said shell being closed at the region of smaller diameter and having a relatively small opening at the region of greater diameter, a conductor projecting through said closed end and being insulated therefrom, an electric resistance heater mounted on said conductor within said shell, said heater having one terminal thereof connected to said conductor and the opposite terminal to said shell and a coating of material on the interior of said shell having a materially higher electron emissivity than said shell.
10. 5. In an electrical discharge device a thermionic cathode comprising a funnel-shaped elongated, hollow body having a cover for its wide end, said cover being provided with a restricted opening, a material of high electron emissivity within said body, means for heating said body, an anode remote from said cathode, an envelope, and a charge of gas therein.
15. 6. An electric discharge device containing a gas at a sufficiently high pressure to operate with a positive ionization discharge, and being provided with a thermionic cathode comprising an elongated, hollow body, the interior of which is coated with electron-emitting material, and a separate heater for said hollow body, the diameter of said body increasing along its major axis and having an opening at the larger end thereof, the heat-dissipating capacity of said larger end being sufficiently great to prevent overheating during operation and the heat-dissipating capacity of the smaller end being such that the period of time required to heat said smaller end to an operating temperature is materially less than the time required to heat the larger end, and an anode remote from said cathode.
20. 7. A gaseous glow lamp comprising an envelope, a charge of neon gas therein at a pressure of about two millimeters of mercury, an anode, and a thermionic cathode spaced apart therein, said cathode comprising a hollow body, the interior of which is presented to said anode, the diameter of said body increasing along its axis and having an opening at the larger end thereof, the heat-dissipating capacity of said larger end being sufficiently great to prevent overheating during operation.
25. 8. A gaseous glow device comprising an envelope, a charge of gas therein, an anode and a funnel-shaped cathode, the interior of which is presented to said anode and the diameter of which increases along its major axis, the smaller end of said cathode being nearest said anode, thereby exposing the exterior surface of said cathode to radiation by a discharge between said electrodes.
